UNITED STATES PATENT OFFICE.

JOHN GREIFENHAGEN, OF RANDOLPH, SOUTH DAKOTA.

TRACE-CARRIER.

1,170,528.

Specification of Letters Patent.

Patented Feb. 8, 1916.

Application filed August 22, 1912. Serial No. 716,504.

To all whom it may concern:

Be it known that I, JOHN GREIFENHAGEN, a citizen of the United States, residing at Randolph, in the county of Brown and 5 State of South Dakota, have invented new and useful Improvements in Trace-Carriers, of which the following is a specification.

My invention relates to trace-carriers.

10 The object of my invention is to provide an advantageous form of trace-carrier which will prevent the disengagement of the carrier from a trace holder.

15 The invention resides in the novel form and construction shown in the accompanying drawings.

In said drawings, Figure 1 is a fragmentary view of harness showing the application of my invention. Fig. 2 is a perspective view of the device embodying my invention, and, Fig. 3 is an end view with part of the body member broken away.

20 Referring to the drawings, 1 designates a suitable harness, 2 the trace holder ring thereof and 3 designates a trace or tug.

The trace-carrier is generally designated 25 4, this carrier is preferably made of yielding or bendable metal to reduce its liability to break, and to provide a means thereon whereby it may be securely fastened to a trace holder ring. Said trace-carrier comprises a substantially triangular, endless, 30 open body 5. Said body 5 has provided integral therewith at right angles thereto a ring 6 which is split so that the parts thereof 35 may be spread apart so as to receive the ring 2 and afterward be brought together so as to loosely retain the member 2 and support the trace-carrier therefrom. On

40 the trace-carrier, below the split ring is provided a hook 7, integral with the carrier and arranged in the same plane as the ring, which hook comprises substantially an inclined arm 8 and a horizontal arm 9, which 45 arm 9 extends through the open member 5 and projects on opposite sides thereof and has the extreme free end in substantial alinement with the plane of the outer edge of said ring and serves as a support for 50 the carrier.

An eyelet member 10 is adapted to engage the arm 9 by means of an opening 11 and has attached thereto the trace or tug 3. In attaching the eyelet member 10 to the

arm 9 of the hook 7, the said member is 55 first inserted into the open member 5 below the arm 9 and at an angle thereto so that the opening 11 may engage the arm 9, whereupon the eyelet member is brought to the vertical position as shown in Fig. 3, 60 so as to hang from said member 9. By means of the specific form of hook the liability of the eyelet 10 to become disengaged from the hook arm 9 is greatly reduced, as the trace or tug 3 may be pulled in either 65 direction without effecting disengagement owing to the fact that the junction of the arms 8 and 9 prevent disengagement in one direction, and also to the fact that the lower or horizontal arm of the open member 5, 70 which lower arm is designated 5', forms an abutment for the eyelet 10 to prevent its disengagement from the arm 9. Furthermore it is obvious that upon outward movement of the body the eyelet member 10, can 75 not become disengaged because of the fact that the horizontal arm extends sufficiently beyond the plane of the carrier so as to cause the horizontal arm 5', at all times to support the eyelet member and the weight 80 of the trace will prevent the eyelet member from working toward the free end of the arm 9. Also the extreme free end of the horizontal arm 9 is curved outwardly at the terminal thereof so that the free end will 85 not dig into the side of the animal to which the device is attached, and thereby provides a leg for coöperation with the ring. This arrangement also facilitates the maintenance of the engagement of the loop 11 with 90 the hook and reduces accidental displacement to a minimum.

Having thus described my invention, what I claim is:—

A trace carrier comprising an integral 95 structure formed of bendable metal, a triangular body portion, a resilient split ring formed at the vertex of said body portion and arranged in a plane at right angles to the plane of the body portion so that portions thereof extend equal distances beyond the plane of the body portion, said ring 100 constituting a suitable support, a hook integral with the vertex and arranged in the same plane as the ring, said hook including 105 an inclined arm projecting beyond the sides of said body portion and a horizontal arm projecting through said body portion, and

the extreme free end of said horizontal arm being curved at the terminal thereof and arranged in a plane substantially flush with the plane of the outer edge of said ring and constitutes a support coöperating with the supporting portion of the ring for supporting the body portion and facilitating the

maintenance of a trace loop in engagement therewith.

JOHN GREIFENHAGEN.
